UNITED STATES PATENT OFFICE

PAUL GUGGENHEIM, OF PHILADELPHIA, PENNSYLVANIA, ASSIGNOR TO PHILADELPHIA METAL DRYING FORM COMPANY, OF PHILADELPHIA, PENNSYLVANIA, A CORPORATION OF DELAWARE

HOSIERY DRYING FORM

Application filed August 24, 1925. Serial No. 51,922.

My invention relates to an improvement in hosiery drying forms and more particularly to the provision of a drying form so constructed as to resist the tendency of hosiery on the form to creep as a result of shrinkage during the drying operation.

Heretofore in connection with the use of hosiery drying forms, and especially of forms of the hollow internally heated metal type, it has been recognized that the hosiery placed on the form in a damp condition has a tendency to creep longitudinally on the form due to its tendency to shrink in the drying process.

Various means have been suggested for holding the hosiery against creeping on the form during the drying operation, but such means have either proved relatively ineffective or substantially complicated and require special manipulation by an operator, which is wasteful of time and delays the drying operation.

Now it is the object of my present invention to provide a hosiery drying form so constructed as to engage or grip the hosiery when applied to it and prevent shrinkage and resultant creeping of the hosiery relative to the form during the drying operation.

Having now indicated, in a general way, the nature and purpose of my invention, I will proceed to a detailed description thereof, with reference to the accompanying drawings, in which there is illustrated a preferred embodiment, and in which—

Fig. 1 is a side elevation of a hosiery drying form embodying my invention.

Fig. 2 is a fragmentary view of a part of a form embodying a modification of my invention.

Fig. 3 is a view of a detail of my invention.

Fig. 4 is a section on line 4—4 Fig. 1.

Fig. 5 is a section on line 5—5 Fig. 1.

The drying form embodying my invention is preferably the usual hollow internally heated type having a foot portion *a*, leg portion *b* and top or welt portion *c*. The form is provided with a base *d* adapted to be secured to the usual support, which, as is well known, also serves as a conduit for the heating medium as steam. The interior of

the form is divided as usual from the base to a point near the toe by a partition *k* in order to permit of circulation of the heating medium.

The form is preferably constructed with relatively flat sides in parallelism, the edges being bevelled as indicated at *e*.

The sides of the welt or top receiving portion *c*, of the form, adjacent the point reached by the end of the welt or top of a stocking placed on the form are provided with a series of transversely extending grooves *f* of substantially V-shape, having one side *f'* extending outwardly and downwardly toward the base of the form and of substantial length, while the other side *f''* extends outwardly and is substantially short. The side *f'* presents a relatively flat downwardly sloping surface, while the side *f''* is preferably slightly curved upwardly and merges into the lower end of an adjacent surface *f'*. The grooves *f* extending transversely to the sides *c* of the welt portion of the form are carried around the edges *e*, which, as a result, have a scalloped effect, formed by projections *h* and depressions *i*.

The grooves *f* may be formed on one side only of the form, or may be formed on both sides. In any event, it is preferable that they be projected into the edges to give the edges the scalloped effect indicated.

It will now be observed that if a stocking *g*, in damp condition, is drawn onto the form, its top or welt portion will overlie the grooves *f* and the scalloped edges. Since the size of the form is such that the stocking is somewhat stretched on the form, it will be engaged in the grooves *f* and by the scalloped edges, and as the stocking tends to shrink in drying, which usually results in its creeping longitudinally of the form, it will engage the grooves and edges more tightly and be prevented from creeping. It will be observed that the tendency to shrink which ordinarily results in a tendency to creep is utilized in connection with the grooves *f* to prevent creeping.

If desirable, though not essentially, the gripping action of the grooves *f* may be supplemented by engaging the stocking in one

of the grooves, through the application to the form of a resilient clamp *j*, formed from, for example, spring steel, and having the form shown in Fig. 3. In use, the clamp *j* is 5 pressed into the form outside of the stocking in a position to bottom the stocking in one of the grooves *f* and clamp it to the form, as shown in Fig. 4.

Referring more particularly to Fig. 2, a 10 portion of the edges *e* of the top or welt receiving portion *c* of the form may be projected, the projected portion being scalloped to form in the edges alternate projections *h'*, which extend beyond the true edge of the 15 form, and depressions *i'*, the bottoms of which are at about the true edge of the form. The projections and depressions are preferably curved and merge into one another.

When a stocking is placed on a form having a top receiving portion as shown in Fig. 2, the top or welt portion will be engaged by the projections *h'* and will engage in the depressions *i'* so that the stocking will be held 20 from creeping. The tendency to shrink will increase the grip and offset the tendency to 25 creep.

In the operation of the form embodying 30 my invention, which will be clear from the above description, there is required no special manipulation. The stocking is drawn on the form in the usual manner and the top or welt overlies the grooved portions of the sides and the scalloped portions of the edges, which 35 grip the stocking, but do not interfere with its ready application to or removal from the form. As the stocking dries on the form, it tends to shrink and its shrinkage causes it to more tightly grip the form, so that shrinkage, which ordinarily results in creeping, aids 40 the grooves and scalloped edges in preventing creeping.

Having now fully described my invention, what I claim and desire to protect by Letters 45 Patent is:

1. A hosiery drying form consisting of 50 foot and leg portions, said leg portion having opposite faces tapering at their edges towards each other to form margins of less thickness than the thickness of the central portion of the leg portion, a projecting rib 55 extending completely about the faces and margins of the leg portion of the form, and a clip for engaging a stocking on the form at the side of the rib away from the foot portion.

2. A hosiery drying form consisting of 60 foot and leg portions, said leg portion having opposite faces tapering at their edges towards each other to form margins of less thickness than the thickness of the central part of the leg portion, each face of the leg portion having a projecting rib extending 65 transversely thereof, and a clip for engaging a stocking on the form at the sides of the ribs away from the foot portion.

3. A hosiery drying form consisting of 70 foot and leg portions, said leg portion having opposite faces tapering at their edges towards each other to form margins of less thickness than the thickness of the central part of the leg portion, a series of spaced 75 projecting ribs extending completely about the faces and margins of the leg portion of the form, and a clip engageable with a stocking on the form between adjacent ribs.

4. A hosiery drying form consisting of 80 foot and leg portions, said leg portion having opposite faces tapering at their edges towards each other to form margins of less thickness than the thickness of the central part of the leg portion, each face of the leg portion having a series of projecting ribs 85 extending transversely thereof, and a clip for engaging a stocking on the form between adjacent ribs.

In testimony of which invention, I have hereunto set my hand, at Philadelphia, Pennsylvania, on this 6th day of August, 1925.

PAUL GUGGENHEIM.
